UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

OILING DEVICE FOR FLAT-PISTON MOTORS.

Application filed February 23, 1924. Serial No. 694,513.

To all whom it may concern:

Be it known that I, CHARLES C. HANSEN, a citizen of the United States, and a resident of Easton, county of Northampton, and 5 State of Pennsylvania, have invented a certain Oiling Device for Flat-Piston Motors, of which the following is a specification accompanied by drawings.

This invention relates to motors of the flat 10 piston type, but more particularly to devices for supplying lubricant thereto.

As it is well known, motors of the flat or square piston type are hard to maintain tight, because of the large bearing area of 15 the piston exposed to unbalanced pressure and the small amount of clearance allowed between the piston and the cylinder wall. These conditions create excessive wear and for this reason, lubricant should be applied 20 to the bearing surfaces in sufficient quantities to minimize the wearing and to prevent excessive leakage.

It is accordingly an object of the invention to supply oil to an engine of this type 25 in a manner to insure efficient oiling and also so as to insure that the oil will reach all bearing surfaces equally and thoroughly. In the practice of this invention, the oil is supplied to the engine in the form of vapor 30 carried along by the motive fluid by a device which automatically regulates the amount of oil so supplied and eliminates any surplus or admission of oil in the form of drops or liquid. In this manner the oil is carried by 35 the motive fluid into the bearing surfaces evenly.

Other objects of the invention will become apparent from the following description taken in conjunction with the drawings, 40 showing a form which the invention may assume in practice and in which—

Figure 1 is an end elevation of the invention, the throttle valve chest of the oiling device being shown in section to more clearly 45 illustrate the operation of the latter.

Figure 2 is a vertical longitudinal cross section taken along the line 2—2 of Figure 1 looking in the direction of the arrows, showing the main bearing areas to be lubricated.

Figure 3 is a longitudinal section through a portion of the oiling device to more clearly show the manner in which the oil or lubricant is mixed with the motive fluid.

Figure 4 is a cross section taken through

one of the lubricating cartridges employed in the oiling device, showing the manner in which it is constructed.

Figure 5 is a side view of the cylinder with the front cylinder cover removed, and 60

Figure 6 is a side view of the front cylinder cover and valve chest.

Referring to the drawings, the engine shown is of the flat or square piston type, and comprises a cylinder frame A integral with the foot or base B upon which the engine is mounted and has two heads, the head C forming a support for the crank shaft D, there being bearings E provided therefor and another bearing not shown and the head F forming the cover. The frame piston G is adapted to slide between the heads C and F and the frame A. The frame piston G is actuated by motive fluid introduced alternately at the ends of the cylinder formed by the heads C and F and frame A, as shown in Figure 2. An inner piston H is mounted on the crank pin J of the shaft D and is actuated by motive fluid introduced alternately at the top and bottom of the cylinder. The two pistons G and H cooperate in a well known manner to resolve the force of motive fluid actuating thereagainst into a circular motion at the crank pin J and drive shaft D. The arrangement of ports and passage for distributing the motive fluid to the various parts of the cylinder may be of any of those well known in the art and as this invention does not reside therein a detailed description thereof is omitted. 90

The throttle valve chest K is formed integrally with the cylinder head F and is provided with a cylindrical bore L and suitable supply and exhaust ports. In the position of the spool valve O shown in the drawing, the port P acts as a supply passage to the cylinder and motive fluid enters the valve chest through the passage Q. The port R acts as an exhaust port through which motive fluid is educted to a passage S to atmosphere. When the valve O is in position to reverse the direction of rotation of the engine a port T corresponding to the port P, is in communication with the exhaust passage S and the port R formerly used as an exhaust port is placed in communication with the supply of motive fluid through the passage Q and then serves as an admission port for the engine. Integral with the throttle valve chest K there is formed an 100 105 110

oil reservoir U which is associated with the valve chest through the medium of absorbent cartridges V and a restricted passage W. The cartridges V are held in place in the bores X in the frame of the reservoir U by means of a rod Y extending therethrough and springs Z about the rod press the cartridges into position. The cartridges V are insertable in the oil reservoir through openings b closed by means of suitable plugs c. There are two cartridges V provided for the reason that it may be desirable to place the engine on one of its sides. In this case at least one of the cartridges will be supplied with oil by gravity because of the manner in which the cartridges are disposed with respect to the reservoir U.

Between the restricted passage W and the cartridges V there is an oiling chamber d into which the motive fluid to be saturated with oil is introduced and continually kept in motion by the pulsations caused in the supply line by the cut-off and admission of the motive fluid to the engine cylinder. In other words, the motive fluid in the valve chest is caused by the pulsations to enter and leave the oiling chamber cartridges and reservoir through the restricted passage W. Slight fluctuations in pressure against the face of the cartridges V cause the motive fluid to enter the cartridges and reservoir U and to pass out upon a reduction of pressure, carrying oil in a vapor along with it and then out through the restricted passage W into the port P or R depending upon the position of the throttle valve O.

The construction of the cartridge is indicated in Figure 4. A sheet of absorbent fabric f and a sheet of wire netting f' are wrapped together spirally to form a cylindrical cartridge, as shown. The wire netting reinforces the absorbent fabric and additionally makes the cartridges more porous so as to permit more of the motive fluid to penetrate the structure. The ends of the cartridge may be faced with perforated plates g as shown in Figure 3 to reinforce the square ends.

The throttle valve O may be operated in any suitable manner. In the drawing, it is shown operated by a pinion h on which is mounted a suitable handle i which meshes with a rack face k attached to the end of the valve O. The end of the bore l is closed by a plug o held in position by means of a pin p. The valve may be held in its central position by coil springs q, interposed between the plug o and the ends of the valve O. The tension of the springs q tends to hold the valve O centrally, so that ports P, R, and T are all covered.

On account of the arrangement of the ports for admitting the motive fluid to the cylinders, the piston H is pressed against the face of the cylinder head C with consid-

erable pressure. To avoid excessive wearing of the bearing faces of the cylinder head C and the piston H due to the pressure and sliding of these faces on each other, additional lubrication is provided. For this purpose a reservoir r is formed integrally with the cylinder A and from two sumps r' on the ends of the reservoir passages s conduct oil to an annular oil groove t in the face of the cylinder head C. As the piston H rotates it wipes oil from the groove t over the face of the cylinder head C to maintain a proper condition of lubrication. The location of the sumps r' assures that the oil will be supplied to one of the passages s and thence to the oil groove t regardless of the position in which the motor is mounted on its base, that is to say, on either side or upright. Occasion often arises when it is desirable to tilt the motor to one side or the other in which conditions it is never necessary to turn the motor upside down since all inclinations of the drive shaft D may be obtained without so doing. For all such positions the supply of oil by gravity is assured with the arrangement of the apparatus as above described.

The engine illustrated in the drawings is of the type known to those skilled in the art as the square piston in which there is provided a square cylinder A within which a frame piston G is adapted to reciprocate from side to side as shown in Figure 5 and within the frame piston G there is provided an inner or rotary piston H which reciprocates with respect to the frame piston G as a cylinder at right angles to the direction of motion of the frame piston G. The motion of the two pistons G and H is resolved into a rotary motion in the crank pin J which is suitably journaled in the rotary piston H. Distribution of the motive fluid is effected for actuating the pistons G and H by means of a plurality of ports 2 formed in the rotary piston H and which lead through suitable passages to the four faces of the pistons G and H which are adapted to be exposed to steam or air pressure. There being four such faces, four ports are provided in this instance. The ports 2 are arranged to register successively with a central inlet port 3 in the cylinder head F, which communicates with the passage R in the valve chest. Since the piston H rotates, the ports 2 register successively with the admission port 3 to admit motive fluid to the end faces of the pistons G and H in succession and produce rotation of the crank shaft D. For exhausting motive fluid from the cylinder A, four ports 4 are provided in the cylinder head F which are associated with the ports P and T leading to atmosphere in one position of the throttle valve O. Each of the ports O is adapted to register successively with the ports 2 in the rotary

piston H to exhaust motive fluid from the cylinder. It is understood that if it is desired that the crank shaft D be rotated in one direction, the central port 3 is used as an admission port and the ports 4 act as exhaust ports and that when it is desired that the crank shaft D rotate in the opposite direction, the ports 4 then are used as admission ports and the central port 3 then acts as an exhaust port.

The throttle valve O is constructed to produce the desired change. Thus, with the throttle valve in the position shown in Figure 1 the ports 4 act as admission ports; and with the throttle valve O at the opposite end of its travel the central port 3 acts as the admission port.

In the operation of the device, with the throttle valve O in position shown in Figure 1, pressure fluid entering the throttle valve chest K through the passage Q will pass to the cylinder through the port P. During the passage of the pressure fluid through the channels described, a portion of the pressure fluid will pulsate into the oiling chamber d and become saturated with oil. The oil thus carried from the oiling chamber d will intermingle with the pressure fluid passing through the valve chest K and will pass therewith into the cylinder. In this manner, lubricant in sufficient quantities is at all times supplied to the pistons during the operation of the machine. Upon reversal of the throttle valve O, pressure fluid entering the valve chest K will enter the cylinder through the port R for reversing the direction of the engine. With the engine running in this direction pressure fluid will be exhausted directly from the cylinder through

the port T and thence through the passage S. It will be seen that in this position of the throttle valve O, the oiling chamber d will still remain in communication with the valve chest and oil for lubricating the engine will be supplied to the pressure fluid in the manner described.

I claim:

1. In a reciprocating fluid acuated motor, a cylinder head, a valve chest on said cylinder head, an oil reservoir formed integrally with said cylinder head, an oiling chamber within said reservoir communicating with a port in said valve chest, a pair of cartridges closing the ends of said oiling chamber adapted to be impregnated by oil from the reservoir and to deliver such oil to the motive fluid pulsating into the said oiling chamber from said valve chest, a rod extending through said cartridges and springs about said rod for maintaining said cartridges in position.

2. In a reciprocating fluid actuated motor, a cylinder head, a valve chest on said cylinder head, an oil reservoir in said cylinder head adjacent said valve chest and integral therewith, a supply port in said valve chest associated with said reservoir and a pair of absorbent cartridges interposed between said reservoir and said supply port, each adapted to supply oil by pulsations of said motive fluid in the supply port, said absorbent cartridges being positioned with respect to each other and said reservoir, so that at least one of the said cartridges is submerged in all operative positions of said motor.

In testimony whereof I have signed this specification.

CHARLES C. HANSEN.
